FOOT TREATING DEVICE

Louis B. Triplett, Pasadena, Calif.

Application August 10, 1938, Serial No. 224,075

2 Claims. (Cl. 128—25)

My invention relates to an improvement in a device for flexing, exercising and massaging the human foot, for the purpose of adjusting the joints and bones thereof into proper and normal relative positions, relaxing the muscles and consequently resting the foot, and re-establishing circulation of blood so as to overcome the effects of stasis.

It is an object of the present invention to provide a device which may be rested upon a suitable support, such as a floor, and into engagement with which the foot may be brought, this device being adapted to be actuated by a substantially lateral movement of the foot, that is to say, in a direction substantially horizontal or which crosses a vertical line or plane.

It is a further object of the invention to provide a foot treating device of the character described, having an arch engaging member to bear against the bottom of the foot, and a bridge member adapted to extend over the upper portion of the foot, these members being supported so as to be moved in lateral direction by a foot which is placed in engagement with same and being so arranged that flexing action is applied to the foot structure in response to the movement of the arch and bridge members by the foot in engagement therewith.

It is a further object of the invention to provide a foot-treating device of the above character, having a foot engaging member mounted eccentrically pivoted levers which permit a swinging thereof on arcs so positioned that said swinging movement will cause pressural engagement of the foot engaging members with the foot in a manner to perform a desired treatment of the foot.

It is a further object of the invention to provide a base, carrying spaced pivots, a pair of lever members extending upward from said pivots in crossing relation, with foot-engaging members supported on the upper portions of the levers, these foot-engaging members being so arranged that as the levers are swung, one of the members will press against one portion of the foot and the other of the members will press against another portion of the foot.

It is a further object of the invention to provide a device of the above character wherein the foot-engaging parts are relatively adjustable to enable the bringing of different parts of the foot into engagement with one of the members while the other of the members is in engagement with a selected other part of the foot.

Further objects and advantages of the inven-

tion will be brought out in the following part of the specification.

Referring to the drawing which is for illustrative purposes only:

Fig. 1 is a perspective view of a simple and preferred form of my invention.

Fig. 2 is a side elevation drawn to reduced scale and showing the manner in which the foot is caused to engage the cooperating parts of the preferred form of the invention.

Fig. 3 is a diagrammatic elevational view showing another relation of the lever members and supporting pivots therefor, by which the stated accomplishments of the invention may be attained.

The preferred form of the device has a pair of foot-engaging members, 5 and 6, which are moved relative to selected portions of the foot being treated in such manner that the foot will be flexed, adjusted, exercised and massaged. 20 The member 5 comprises a knob or body, preferably made of resilient material, such as sponge rubber or the like, and intended to be brought into engagement with the under portion of the arch of the foot, as shown in Fig. 2, although by 25 sliding the foot forward from the position in which it is shown, the arch engaging member 5 may be brought into engagement with the bottom of the heel, or, by moving the foot rearward, the ball of the foot may be brought into engagement with member 5. The member 6 is intended to be brought into engagement with an upper portion of the foot in a position offset from the point of engagement with the arch engaging member 5. This member 6 may be best 30 referred to as a bridge member, for the reason that it includes an arcuate metal wall 8, lined with a suitable resilient material or padding 9, such as felt, which may be secured to the wall 8 by means of rivets 10.

The arch-engaging member 5 is secured to the upper end of a lever 11, comprising a bar or rod having a lower end portion 12 bent at right angles so as to engage pivot means 13, consisting of a metal tube or channel formed along the 45 front edge of a stamped plate 14, which is secured by rivets 15 to a base plate 16, which may have a layer of anti-skid material 17, such as rubber, secured to the lower face thereof.

The bridge member 6 is supported in a position 50 forward of the arch engaging member 5 by a lever 18, which extends rearwardly in crossing relation to the lever 11, to a pivot means 19 disposed on the plate 16, in spaced relation to the pivot means 13 and to the rear thereof. This 55

lever 18 is made from a bar 20, at 21 and 22 so as to provide a pair of lever arms 18a and 18b and a base or pivot portion 23, which passes under the pivot means 19. The pivot means 5 19 consists of a pair of inverted channel portions formed along the rear edge of the plate 14. The pivot portion 23 of the lever 18 may be provided with a stop for limiting rightward or clockwise rotation of the member 18, such stop 10 consisting of a U-shaped bend 24 in the center of the pivot portion 23. The portions 18a and 18b bend forwardly at 25 so as to cross the transverse plane defined by the member 11, and the end portions 26 thereof are bent so as to slope downward and forward, these end portions being received in loops 27 formed at the edges of the arcuate metal wall 8. A slideable metal plate 28 is provided with rolled tubes 29 at the ends thereof to engage the upper portions 30 of the lever arm members 18a and 18b between the bends 25 and the bridge member 6, there being a central opening 32 in the slideable plate 28 through which the upper portion of the lever member 11 projects. Within the limits of the movement of 20 the slideable plate 28 on the rod portions 30, the arch engaging member 5 may be adjusted toward or away from the bridge 6. A tension spring 33 has its forward end connected to an opening 34 in one of the lever arms 18b and has its rear 30 end connected at 35 to the base 16, this spring yieldably rotating the lever 18' in clockwise direction to an upright position wherein the stop 24 engages the base 16.

In the use of the device, it is normally rested 35 upon the floor and the foot to be treated is placed as shown in Fig. 2, and the front part of the foot, such as the toes, or the toes and the metatarsal joints, are passed under the bridge 6. The arch of the foot is brought into engagement with 40 the arch engaging member 5 at a position where upward pressure is desired, the foot is then shifted forward, or in the direction of the arrow 35 of Fig. 2, to swing the bridge 6 toward the position indicated by the dotted lines 6a and to swing the arch engaging member to the position indicated by the dotted lines indicated by the lines 45 5a. Owing to the fact that the member 5 swings on an arc indicated by dotted lines 36 generated around the pivot means 13, and the bridge 6 moves along on arc 37, generated around the pivot means 19, the bridge 6 will move downward relative to the arch engaging member 5, or conversely the arch engaging member 5 may be considered as having an upward movement relative 50 to the bridge 6, with the result that the arch engaging member 5 presses upward against the bottom of the foot and the bridge presses downwardly against the upper forward part of the foot, thereby convexly flexing the arch of the foot. In proceeding with this treatment, the 55 foot may be shifted from one side to the other and may be moved forwardly and rearwardly relative to the foot engaging parts 5 and 6, so

that the scope of the treatment may be distributed over a relatively large area, thereby accomplishing complete manipulation massaging effect and exercising of the foot structure.

In Fig. 3, I show a base 16a having a front 5 pivot 13a and a rear pivot 19a. In this form of the invention, the arch engaging member 5a is mounted on the upper end of a lever 11a, which slopes rearward instead of being placed substantially vertically like the similar part 11 shown 10 in Figs. 1 and 2. The bridge 6a is mounted at the upper end of a lever 18 which is pivotally secured to the plate 16a by the pivot 19a. In this alternative device, the arch engaging member 5a swings upward, as indicated by an arrow 40; 15 whereas, the bridge 6a swings downward as indicated by an arrow 41. Accordingly, when these parts are swung in engagement with a foot to be treated, the member 5a' will press upward against the arch of the foot and the bridge 6a 20 will press downward on the frontal portion of the foot, thereby producing the desired flexion of the foot structure. It will be perceived that in this alternative form of the invention I have shown how the levers 11a and 18' may be placed 25 in crossing relation so as to produce relative upward and downward swinging movement of the foot engaging members in response to a movement having a general horizontal direction.

I claim as my invention:

1. In a foot treating device of the character described, the combination of: a bridge member to pass over an upper portion of the foot; an arch engaging member placed so as to bear against the bottom of the foot; a pair of levers, 35 one each of which supports one of said members; and pivot means for said levers arranged eccentrically so as said levers are swung, said members will have a relative movement respectively downward and upward with regard to the foot 40 being treated.

2. In a foot treating device of the character described, the combination of: a base; a first pivot carried by said base; a lever extending upward from said pivot; an arch engaging member carried by said lever to engage the bottom of a foot to be treated; a second pivot carried by said base in a position offset from said first pivot; a second lever extending upward from said second pivot and crossing said first lever; and a top engaging member carried by said second lever, said top engaging member having a portion adapted to engage the top of the foot which is engaged by said arch engaging member, the swinging of said levers on said pivots causing said arch engaging member and said top engaging member to have relative upward and downward movement whereby said arch engaging member will be caused to bear upward against the bottom of the foot and the top engaging member will be caused to press downward against the top of the foot.

LOUIS B. TRIPLETT.
